UNITED STATES PATENT OFFICE.

ALPHONSE NEWHOUSE, OF SAN FRANCISCO, CALIFORNIA.

BLADE-SHARPENER.

1,271,930.

Specification of Letters Patent.

Patented July 9, 1918.

Application filed June 17, 1916. Serial No. 104,292.

To all whom it may concern:

Be it known that I, ALPHONSE NEWHOUSE, a citizen of the United States, residing at the city and county of San Francisco and 5 State of California, have invented new and useful Improvements in Blade-Sharpener, of which the following is a specification.

This invention relates to a device for sharpening blades and is here illustrated as 10 applied for the sharpening of double edged blades such as are used in connection with safety razors.

The invention resides in an improved tilt-able blade holder having means adapted for 15 coöperation with a reversing device whereby the blade may be sharpened on both edges.

Specifically it consists of a pair of arms that project outwardly from one end of the 20 tilting holder, these arms being acted on by an elastic reversing device, which engages the arms after the blade leaves the hone or strop, and revolves the holder, so that the blade will be reversed, and upon the return movement the opposite side and edges will 25 be presented to be acted upon.

It also comprises details of construction which will be more fully described by reference to the accompanying drawings, in 30 which—

Figure 1 is a perspective view of the device.

Fig. 2 is a separate view of the reversing arms.

Fig. 3 is a side view of the blade holder.

Fig. 4 is a plan view.

Fig. 5 is a section through line 5—5 of Fig. 3.

Fig. 6 is a modification of the reversing arms.

Fig. 7 is a fragmentary section through the blade holder.

The invention contemplates an improved blade sharpener comprising means for holding and moving the blade over an abrading 45 surface, a rapid and accurate automatic means for alternately presenting the edges of the blade to the abrading surface after each stroke of the blade-holding means, and automatic means for reversing the blade and 50 presenting the reversed side thereof to the abrading surface, as desired.

In my present illustration I have shown a hone A, mounted upon a guiding support comprising a base B, and tracks 2 fixed to the 55 base upon each side of the hone. A carrier is provided for carrying the blade while be-

ing sharpened, which carrier comprises a yoke 3, a handle 4 secured to the yoke, an axle 6 to which the yoke is connected at its extremities, and wheels 5 frictionally journaled on the ends of the axle. This axle 60 serves to hold the blade 7 which is to be sharpened.

As here shown this axle 6 is made in two parts, one of which is movable with relation 65 to the other to form a clamp, so that the blade 7 may be securely held between these two portions with its edges projecting substantially equally upon each side of this axle. The wheels fit upon the axle with sufficient 70 friction so that when these wheels resting on the tracks 2 are moved backward or forward, they will cause the axle to tilt and bring either edge of the blade down upon the hone, 75 above which the axle extends at such a distance that when the blade is forced down upon the hone it will have the proper angle for sharpening.

It will be manifest that the reciprocation of the blade will cause the axle carrying the 80 blade to tilt first in one direction and then in the other, thus alternately bringing the lower edges of the blade into contact with the hone.

In order to reverse the blade and present 85 the opposite edges, I have shown the following device: Upon the side of the base is fixed a spring arm 8 forming a laterally yieldable stop and guide. In Fig. 1 I have shown this arm as having one of its ends secured to the 90 side of one of the tracks 2 and the other end is movable on account of the elasticity so that it will swing outward upon the guide pin 9, when actuated for this purpose. At the end of the axle 6, and outside of one of 95 the wheels 5, is a cam or bar 10 having its ends turned outwardly and forming points 11 and 12 each formed with a cam face. These points are bent to form cam surfaces, as shown in the drawing, so that one of them turns downwardly and the other upwardly 100 when the bar is in a position approximately parallel with the blade 7.

The operation will then be as follows: When the handle 4 is pushed it carries the 105 frame 3 and the wheels 5, resting upon the track 2, and the blade will be turned downwardly by the friction of the wheels upon the axle on which they turn, until the edge of the blade rests upon the hone at the 110 proper angle. Then it is pushed the length of the hone and then the motion is reversed,

The reversing of the motion causes the blade to turn so that its opposite edge rests upon the hone where it continues to rest until it has reached the end. The further motion of 5 the carrier will bring the edge of the blade off of the hone and this action will cause the blade to turn downwardly. The arms 10 will partake of this motion until the point 12 rests upon the edge of the plate 8 which 10 it follows for a short distance, and by reason of its upturned angular position it forces the plate away from the track, sliding upon the support 9 until the point 12 drops below the plate 8 and the wheels continue to turn 15 until the arms and blade have turned into a substantially horizontal position with the arm 11 above the edge of the plate 8. This plate then springs back into its normal position and the arm 11 will ride on the top edge 20 of the plate until it passes the end and the rollers will then revolve in an opposite direction and allow the blade to tilt downwardly toward the direction in which it is moving until the edge then presented rests upon the 25 hone and it may then be moved forward so that the hone will act upon the edge thus presented.

The movement of the carrier with the blade backward and forward will thus act 30 first to hone the edges which are presented downward. Then as the carrier is drawn backward until the blade is free from the hone, the blade will be reversed and when again returned to the hone the opposite side 35 and its edges will be presented for operation.

In Fig. 6 I have shown a modification of the device 8, in which a cam composed of 40 two screw sections 13 is fixed to a turnable shaft 14, so that the inner ends are fixed to the shaft and the outer ends make a half spiral turn opposite to each other, and these free ends are elastic and produce the desired action in turning the blades, the part 8 45 being fixed.

It will be manifest that other equivalent modifications may be made to produce the herein-described result and I consider such changes as being within the scope of the 50 present application and claims.

Having thus described my invention, what I claim and desire to secure by Letters Patent is—

1. In a blade sharpener, spaced tracks, an 55 interposed abrading element beyond which the tracks extend at one end, a blade holder, a support rotatably carrying the latter and movable over the tracks, and means arranged beyond the abrading element permitting free rotation of the holder when the latter is moved from the abrading element 60 and engaging with the support on movement of the latter toward the abrading element for retaining the holder in proper position 65 to engage the abrading element.

2. In a sharpener for double edged blades, a fixed abrading element, a pivotally mounted blade holder constructed to hold a blade between its cutting edges, means for traversing said blade holder in opposite directions over the abrading element, and rocking it to bring a side of one edge of the blade against the abrading element on movement in one direction and on reverse movement to bring the corresponding side of the 75 opposite cutting edge against said abrading element, and means arranged beyond one end of the abrading element and in the path of movement of the blade holder for contacting therewith and turning it over to present to the abrading element the opposite sides of the cutting edges of the blade. 80

3. In a blade sharpening device, a supporting body having a trackway, a blade holder formed to hold a blade between its 85 edges, means supporting the holder for reciprocatory movement along the trackway, and means permitting rotation of the holder on movement of the supporting means in one direction and arresting the 90 holder against back movement on reverse movement of the supporting means. 95

4. In a blade sharpener, spaced tracks, an interposed abrading element beyond which the tracks extend at one end, a blade holder 100 having shaft extensions, wheels frictionally mounted on the latter for movement over the tracks, to effect rotation of the holder on movement from the abrading element, and means for arresting the holder against rotation on movement thereof toward the abrading element. 105

5. The combination in a blade sharpener, of a fixed abrading element, a holder in which the blade is supported above the 110 abrading element, tracks upon each side of said element, rollers frictionally journaled on said holder and adapted to travel on said tracks and to tilt the holder and blade to bring opposite edges of the blade in contact with the abrading element alternately at each reciprocation, a spring guide secured at the side of a track, and cam arms fixed on the outer end of said holder adapted to contact with said guide to reverse the holder and blade and to guide the reversed side of the blade to the abrading element. 115

6. In a blade sharpener, an abrading element, a rotatable blade holder movable over the element, a cam fixedly connected to the 120 holder to be rotated thereby and provided with a forward cam face, and a laterally movable part adjacent the path of the holder adapted to be engaged by the cam face to be shifted from its path on rotation of the cam 125 in one direction and to be engaged by said cam on rotation of the latter in a reverse direction for holding the cam and the blade holder against rotation.

7. In a blade sharpener, an abrading ele- 130

ment, a guiding support, a rotatable blade holder, means mounting the latter on the support for reciprocating movement over the abrading element and for rotating the holder when moved beyond said element, a yieldably mounted guide arm on the support, and a fixed arm rotatable with the holder and adapted to shift the arm from its path in one direction and be arrested thereby to prevent turning of the holder in the reverse direction of rotation.

8. In a blade sharpener, an abrading element, a guiding support, a rotatable blade holder, means mounting the latter on the support for reciprocating movement over the abrading element and for rotating the holder when moved beyond said element, and means permitting the rotation of said holder on movement of the latter in one direction and arresting the holder against reverse rotation on movement of the latter in the opposite direction, said last means in-

cluding a fixed part and a yieldable part, one part being connected with the holder.

9. In a blade sharpener, a rotatably mounted blade holder, a support therefor, frictional drive means for the blade holder mounting the same on the support, a stop member on one of said first two named elements, and a cam member carried by the other of said first two named elements for coöperation with the stop member whereby the holder may rotate in one direction and is held against rotation in the opposite direction, one of said members being yieldably mounted.

In testimony whereof I have hereunto set my hand in the presence of two subscribing witnesses.

ALPHONSE NEWHOUSE.
